UNITED STATES PATENT OFFICE.

JONATHAN O. FOWLER, JR., OF NEW YORK, N. Y., ASSIGNOR TO ALEXANDER EVERETT HUNT, OF SCRANTON, PENNSYLVANIA.

GLASS-TUBE CUTTER.

SPECIFICATION forming part of Letters Patent No. 476,626, dated June 7, 1892.

Application filed February 5, 1891. Serial No. 380,388. (No model.)

To all whom it may concern:

Be it known that I, JONATHAN O. FOWLER, Jr., a citizen of the United States, and a resident of New York, county and State of New York, have invented a certain new and useful Improvement in Glass-Tube Cutters, of which the following is a specification.

My invention relates to appliances designed to incise articles—as, for example, glass tubes or plates, &c., and has for its object the provision of a device simple in construction, cheap in manufacture, and efficient in practical use.

To attain the desired end my invention consists in the construction and arrangement of parts hereinafter first fully described, and then pointed out in the claims.

In the drawings which form a part of this specification, Figures 1 and 2 represent side elevations of articles constructed according to my invention, and Figs. 3, 4, and 5 are partial side elevations of other tools so constructed.

Like letters of reference, wherever they occur, indicate corresponding parts in all figures.

Referring again to the drawings, A A' represent two practically parallel jaws or arms adapted and preferably arranged to be normally held somewhat apart, as by springs B B', and upon manipulation, as by use of a handle, as C or H, to approach each other ordinarily on opposite sides of the material to be operated upon and to continue in a parallel or approximately parallel relation while so approaching each other or traveling away from one another. It is obvious that many methods of construction and arrangement of parts may be utilized to accomplish this action of the two arms or jaws A A'; but one of the most preferable instruments of this description is made and operated in the following manner: The rear portion A³ of the lower arm or jaw A' is provided with two standards a a', which work in two orifices a² a³, formed in the rear part A² of the upper arm A, on which standards are placed spiral springs B B', which springs serve to separate the parts. The jaws A A' may by being grasped directly by the hand be caused to approach each other; but for convenience I prefer to use in connection with the same a

handle or lever C, which controlling-handle is fulcrumed at c to the top of the standard or post a' and serves upon manipulation to cause the upper arm A to approach the lower jaw A'. At or near the extremity of the arm or jaw A is placed a cutting-tool, as the steel disk E, and at the corresponding end of the lower arm A' is preferably located a clamp, as a flange D, which serves as a rest for the glass and which, when the parts are closed together, abuts against the exterior of the glass to be cut, and, together with the cutting-disk E, placed upon the opposite jaw or arm A, serves to hold the glass steadily in position while the incision is being made. It is obvious that a diamond or other glass-cutting material may be inserted in the arm A as a substitute for the rotary cutter E. A collar F is bored or otherwise adapted to slide freely on one of the arms and is preferably formed with a projecting annular flange. This collar serves as a guide for the edge of the glass and may be provided with a set-screw f, by which the collar may be set and secured at any required point on the arm, which is ordinarily marked with graduations of the inch and fractions thereof, as G, in order to show the distance between the edge of the cutter E and the collar F.

Although primarily designed for tubes, yet it is evident that my cutting-instrument may be used to operate upon glass plates, rods, bars, &c.

Another article constructed according to my invention is shown in Fig. 2, where the jaws A A' are provided at their rear ends with inclines A⁴ A⁵, having segmental spiral grooves or threads a⁴ a⁵, adapted and arranged to engage with the interiorly-threaded controlling-handle H in such a manner that upon manipulation of the handle, as by turning the same around, the springs B B' are compressed and the arms or jaws A A' will approach each other, meanwhile maintaining their parallel relation.

In operating with my tool the collar F is first adjusted at any required distance from the cutter E, in cases where a collar is used, and, the instrument being held in one hand and the glass to be cut being inserted between the parallel or approximately parallel

arms or jaws A A', the latter are gently forced toward each other until the glass is firmly grasped by the appliance. Then by moving the glass along between the cutter E 5 and the arm A' an incision will be produced on the surface of the glass and a channel cut therein, whereupon by slightly knocking or jarring the same the portion of the glass desired to be removed will fall off, the separation having occurred on the line previously marked by the rotary cutter E.

It is obvious that either one of the arms or jaws may be stationary, as in Fig. 1, or that both of the same may be adapted and arranged so as to have some movement, as in Figs. 2 and 3, or that, if preferred, the two jaws may normally lie close together, as in Fig. 4, and be pulled apart to admit of the entrance of the glass between the same, in which case the two jaws will recede from each other and again approach one another, maintaining all the while a parallel or approximately parallel relation to each other; or, if so desired, the handle may be attached 25 to one of the movable pins, as represented in Fig. 5.

As it is evident that many slight changes in the construction and relative arrangement of parts might be resorted to without departing from the spirit and scope of my invention, I would have it understood that I do not restrict myself to the particular construction and arrangement of parts shown and described, but that I reserve the right to make 35 such changes, and that

What I claim as new, and desire to secure by Letters Patent, is—

1. A hand glass-cutter consisting of two arms or jaws, one provided with a cutter and the other adapted to serve as a rest or clamp for the glass and arranged to reciprocate, in combination with means for holding the same in a practically parallel position, the two jaws being adapted and arranged upon manipulation to maintain a parallel relation while one 45

arm is moving to and from another or both arms are moving to and from each other, substantially as described.

2. In a hand glass-cutter, the combination, with the two arms, one carrying a cutter and the other a rest for the glass tubing and arranged to reciprocate, of the vertical guides for preventing the arms getting out of the same plane with one another, substantially as described. 55

3. In a hand glass-cutter, the combination, with the two arms, one carrying a cutter and the other a rest for the glass tubing and arranged to reciprocate, of the vertical guides and springs, substantially as described. 60

4. In a hand glass-cutter, the combination, with the two arms, one carrying a cutter and the other a rest for the glass tubing and arranged to reciprocate and to approach and recede from each other parallel, of an auxiliary mechanical device applied upon or connected to the aforesaid arm or arms for operating an arm or arms, substantially as described. 65

5. A glass-tube cutter comprising an arm with a cutter at one end, said arm being attached at or near the other end to another arm carrying a suitable bearing opposite the cutter of the first arm, the bars being so connected as to permit movement toward and from each other and having an auxiliary connecting device connected to or bearing upon each bar and with a projecting lever-handle, whereby the bars may be pressed toward each other during the cutting, substantially as described. 70 75

In testimony of the foregoing specification I do hereby sign the same, in the city of New York, county and State of New York, this 8th day of January, A.D. 1889.
